RAZOR-STROPPING MACHINE.

1,083,665.

Specification of Letters Patent.

Patented Jan. 6, 1914.

Application filed July 27, 1912. Serial No. 711,824.

To all whom it may concern:

Be it known that I, JOHN H. CLAUSS, a citizen of the United States, residing at Toledo, in the county of Lucas, State of Ohio, have invented certain new and useful Improvements in Razor-Stropping Machines; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to stropping machines designed for stropping the blades of razors of all types, and consists in the construction and arrangement of parts herein-after more fully set forth and pointed out 20 particularly in the claims.

The object of the invention is to provide a stropping machine of comparatively simple and inexpensive construction wherein the arrangement is such, that, as the strop 25 is drawn longitudinally through the machine in forward and reverse direction the blade will be successively swung from side to side into contact with the running face of the strop to effect the desired abrasive 30 action, provision being made for resisting the movement of the blade holder by spring tension whereby said holder shall be returned to the neutral position centrally between the side portions of the strop when- 35 ever tension upon the strop is relaxed, thereby causing the blade to swing away from the face of the strop so as to obviate the strop becoming cut upon a change in the direction of movement thereof. The above 40 object is attained by the mechanism illustrated in the accompanying drawings, in which:—

Figure 1 is a general view in perspective of a stropping machine embodying my invention. Fig. 2 is a horizontal section through the machine on a larger scale, showing the parts in the inoperative position with the blade holder held upon its pivot centrally between the side portions of the strop. Fig. 3 is a similar view of the device in an operative position, showing the blade holder swung by the operation of drawing upon the strop so as to carry the edge of the blade into contact with the outwardly 55 running portion thereof. Fig. 4 is a view

similar to Fig. 3, showing the blade holder swung in the opposite direction. Fig. 5 is a fragmentary view in section, showing the connection between the pivoted actuating frame and the pivoted blade holder, where- 60 by the blade holder is caused to swing from side to side as the actuating frame is oscil- lated. Fig. 6 is a fragmentary view in per- 65 spective, illustrating the parts shown in Fig. 5 and in addition thereto the spring element through the function of which the blade 70 holder is returned to the central or neutral position when tension upon the strop is re- lax- 75 ed.

Referring to the drawings by the charac- 70 ters of reference marked thereon, 1 designates the side portions of the main tri-lat- 75 eral frame, which are connected by the in- tegral cross pieces 2 at the end in which is mounted the swiveled ring 3. The side por- 75 tions 1 of the frame are connected near the front by the rods 4 whose ends are riveted in the side pieces, and which are embraced by the sleeves 5. At the front the side pieces are connected by the rod 6, embraced by a 80 sleeve 7.

Mounted between the sides of the main frame, at the rear thereof, is a pivoted or oscillatory frame comprising the end por- 85 tions 8 connected at their extremities by the shafts 9 embraced by the sleeves 10. Riveted at its ends in the side pieces of the main frame is a rod 11 which passes through the end portions 8 of the oscillatory frame and forms the axis upon which said frame oscil- 90 lates.

The blade holder 12 is provided with the converging jaws 13 between which a blade 14 is adapted to be inserted, there being within the blade holder a curved spring 15, 95 the tension of which is exerted to force the tapering blade outwardly between the con- verging jaws to properly position the blade 100 therein. Each end of the blade holder is provided with a rearwardly projecting ex- 105 tension 16. These extensions are pivotally mounted intermediate the ends thereof upon a rod 17 whose ends are secured in the sides 1 of the main frame. Rigidly mounted at its ends in the terminals of the extensions 105 16 of the blade holder, as clearly shown at 18 in Fig. 5, is a rod 19. Extending in- 110 wardly from each of the end portions 8 of the oscillatory frame is an arm 20 having a notch 21 in the free end thereof which

loosely receives the rod 19, as clearly shown in Figs. 5 and 6, whereby a hinged or jointed connection is effected between the arms 20 of the oscillatory frame and the extensions 5 of the blade holder, which will cause said blade holder to swing upon its pivot or fulcrum rod 17 as the oscillatory frame is actuated.

Mounted upon the fulcrum rod 17 of the 10 blade holder is a coiled spring 22, the terminals of which are formed into rearwardly extending arms 23 and 24, respectively. These arms are bent so as to cross each other, the upper arm 23 lying upon one side of the 15 rods 11 and 19, and the lower arm 24 lying upon the opposite sides of said rods. When the oscillatory frame is swung upon its pivot rod 11 the notched arms 20 of said frame engaging the rod 19, mounted in the 20 terminals of the extensions 16 of the blade holder, will cause the rod 19 to swing in the arc of a circle concentric with the pivot rod 17 on which the blade holder is mounted and will swing the blade holder in the opposite direction to carry the blade into contact with the strop. This movement of the 25 rod 19, if to the right as shown in Fig. 4, will carry it into contact with the spring arm 23 and swing said arm outwardly 30 against the tension of said spring which is held from turning upon the rod 17 by the spring arm 24, the end of which remains in engagement with the rod 11, thereby placing the spring under such tension that when the 35 oscillatory frame is released the spring arm 23 will force the rod 19 back to the neutral or first position, as shown in Fig. 2, thereby returning the blade holder to a position equidistant between the sides of the strop 25. 40 When the pivoted or oscillatory frame is actuated to swing the rod 19 to the left, as shown in Fig. 3, it will be carried into engagement with the spring arm 24, thereby springing said arm outwardly and tensioning the spring 22, the arm 23 in this movement remaining in resisting engagement with the rod 11. The tension stored in the 45 spring 22 by the movement of the arm 24 just described will be exerted to again restore the parts to the neutral or normal position.

The strop 25 is looped over the rollers 10, and the terminals of the side portions thereof passed forwardly through the machine so 50 as to lie against the inner sides of the sleeves 5 upon the rods 4. The ends of the strop are provided with hand rings 26 to enable the strop to be actuated.

As the terminals of the strop are alternately drawn upon to cause it to reciprocate longitudinally through the machine the oscillatory frame will be actuated to swing the blade holder and carry the edge of the blade successively into contact with the outwardly running portion of the strop, as

will be well understood in the art, thereby effecting a proper sharpening of the blade. The tension of the spring 22 exerted through its arms 23 and 24 is such that at the termination of each stroke of the strop in its 70 reciprocatory movement the blade holder will be swung to carry the edge of the blade free from the strop as soon as the tension upon the strop is relaxed at the end of each outward pull, thereby obviating the liability 75 of the strop becoming cut at the instant the direction of movement thereof through the machine is changed. The tension of the spring 22 also normally holds the blade holder centrally between the sides of the 80 strop so that the strop is not likely to become cut when a blade is inserted into or withdrawn from said holder.

Having thus fully set forth my invention, what I claim as new, and desire to secure by 85 Letters Patent, is:—

1. A stropping machine comprising a main frame, a blade holder pivotally mounted therein having a rearwardly projecting end portion, an oscillatory frame pivotally mounted in the main frame, an arm projecting radially from the axis of the oscillatory frame and having a pivotal connection with the rearwardly projecting end portion of the blade holder, a coil spring having projecting 90 terminals, a member lying between said terminals connected with the projecting end portion of the blade holder, and an abutment member also lying between said terminals with which their terminals successively engage.

2. A stropping machine comprising a main frame, a blade holder pivotally mounted therein having rearwardly projecting end portions, a rod mounted in the main frame 105 forming the fulcrum of said blade holder and passing through said projecting end portions, an oscillatory frame, a strop looped over the oscillatory frame for actuating it, a rod mounted in the main frame and passing through said oscillatory frame forming the axis upon which said oscillatory frame oscillates, an arm extending from each end of the oscillatory frame, a rod extending between and connecting the projecting end portions of the blade holder, said arms having notches which engage said connecting rod, a coiled spring mounted upon the fulcrum rod of the blade holder, said spring having extending terminals 110 which lie on opposite sides of the rod connecting the projecting end portions of the blade holder, whereby, as the blade holder is swung through the operation of the oscillatory frame, said spring is placed under tension through the movement of said connecting rod.

3. A stropping machine comprising a main frame, a blade holder pivoted therein, an oscillatory frame pivoted in the main 115

frame, connecting means between the oscillatory frame and the blade holder for imparting movement from the former to the latter, a strop looped over the oscillatory frame for actuating it, a movable member connected with the pivoted blade holder, a coiled spring having terminal portions lying on each side of said movable member, and an abutment member disposed between the terminal portions of said spring to be successively engaged thereby as the oscillatory frame is actuated.

4. A stropping machine comprising a main frame, a blade holder having an extension, a rod set in the main frame on which said extension is pivoted, a rod mounted in the free end of said extension,

an oscillatory frame, a rod seated in the main frame on which said oscillatory frame is pivoted, a strop looped over the oscillatory frame, a coiled spring mounted on the pivot rod of the blade holder, the terminals of said spring extending in the form of parallel arms on opposite sides of the rod mounted in the free end of the extension of the blade holder, the terminals of said spring arms lying on opposite sides of the pivot rod of the oscillatory frame.

In testimony whereof, I sign this specification in the presence of two witnesses.

JOHN H. CLAUSS.
